UNITED STATES PATENT OFFICE.

AMES C. McCANE, OF SEATTLE, WASHINGTON.

CONTROLLER FOR RADIO RECEIVING SETS.

Application filed August 30, 1922. Serial No. 585,247.

This invention relates to electrical controllers and is designed more especially for the purpose of making and breaking the electrical circuits of a radio receiving set.

The object of the invention, generally stated, is the provision of simple, inexpensively constructed and efficient devices of this character which may advantageously be used instead of what is conventionally known as "jack" systems hitherto in use.

The invention consists in the novel construction, adaptation, and combination of parts in a multiple switch including a rotatable contact member which may be used selectively with respect to any of the electrical circuits of a radio receiving set.

In the accompanying drawings,—

Figure 1 is a rear elevational view of a switch-board provided with devices embodying my invention, the circuit connections being shown diagrammatically. Fig. 2 is a sectional view taken substantially through 2—2 of Fig. 1; and Fig. 3 is a front elevation of the switch-board illustrated in the preceding views.

The body 5 of the switch-board may be of any suitable material and in which is journaled the pivot shaft 6 of the movable switch member in the nature of a lever 7 located at the rear of the board and controlled as by means of a knob 8 secured to the end of the shaft in front of the board. Said lever is formed of any suitable non-conducting material and is provided at one side of its axis with a sector shaped arm 9 and at its other side with a relatively narrow arm 10. Secured to the opposite faces of the lever arm 9 are joined metal bridge contact elements 11. Secured to the inner and outer faces respectively of the lever arm 10 and protruding therefrom are contacts 12 and 13 which constitute parts of the receiver connections, so called, of a radio apparatus.

The lead wire 14 of one of said receiver connections is connected by a conductor 15 and the shaft 6 with the contact 13. The lead 16 of the other of said receiver connections is connected by conductors 17 and 18 with the contact 12.

To accommodate rotary movement of the lever 7, said conductor 18 includes a coiled portion 18¹ (Fig. 2) extending about said shaft and separated therefrom by means of an insulating sleeve 19.

Arranged substantially as shown in Fig. 1 and concentrically of the switch axis to be

in engageable relations with the contacts 12 and 13 are pairs of contacts 20, 21 and 22 which are respectively connected to the lead wires 20¹, 21¹ and 22¹ of No. 2 amplifier, No. 1 amplifier, and detector circuits.

The complementary elements of the respective pairs of contacts 20, 21 and 22, as illustrated, are held in approximately the spaced relations in which they are shown with respect to each other by means of insulating blocks such as 23 and supporting posts 24.

At the opposite side of the switch axis from the contacts 20, 21 and 23, is provided an insulating block 25 having secured to the inner side thereof a contact 26 for the lead 26¹ of a battery connection. Secured to the other side of this block and in complementary relations with the contact 26 is the contact 27 for the lead wire 27¹ of the detector filament. Also secured to the block 25 and in spaced relations concentrically of the switch axis are contacts 28 and 29 for the lead wires 28¹ and 29¹ respectively of the filaments of Nos. 1 and 2 amplifier circuits.

The contacts 26, 27, 28 and 29 are arranged substantially as shown for engagement with respect to the bridge contacts 11 and also with respect to the contacts 20, 21 and 22.

30 represents a pointer provided on the shaft 6 for indicating with respect to reference characters—such as "0" "1" "2" "3" "0", for example—provided on the front face of the switchboard the positions of the movable contacts 12 and 13 with respect to the stationary contacts 20, 21 and 22 whereby different adjustments or the connections of the radio circuits may be effected predeterminedly.

By regulating the switch lever 5 by means of the knob 8 to bring the pointer 30 into its illustrated position (Fig. 3) to register with the indicating number "3" will cause the movable contacts 12 and 13 to close the gap between contacts 20 and conductors 15 and 17, simultaneously, with the bridge contacts 11 being brought in electrical connection with the contacts 26 to 29 inclusive.

By turning the knob to have the pointer 30 register with indicating number "2", the lever is brought into position to cut out the No. 2 amplifier contacts 20 and 29 and afford electrical connections between the No. 1 amplifier contacts 21 and conductors 15 and 17 and also between the contacts 26 and 27. The bridge 11 now serves to connect the bat-

- tery contact 26 with the contacts 27 and 28 of the detector and the No. 1 amplifier filament, respectively. By turning the pointer into register with the indicating character 5 "1", only the contacts 22 remain in connection with the conductors 15 and 17; the battery and detector contacts 26 and 27, respectively, remain in electrically, but the amplifier contacts are cut out of circuit.
- 10 By bringing the pointer out of register with any of the characters "1" "2" and "3" as into register with either of the "0", for example, all of the circuit connections are open.
- 15 What I claim, is:—
- A switch of the type described, comprising a unit base adapted to be mounted on a radio panel, a shaft rotatably carried by the base, a rotatable insulating member carried 20 by the shaft and formed with radially projecting arms, contacts projecting in spaced relations from opposite faces of one arm and insulated from each other, contact bridge plates mounted on the remaining arm, a pair of overlying spaced contacts outwardly extended from said support by means of bolts passing through the spaced contacts terminating in the unit base and spacing studs interposed between the unit base and spaced contacts, said contacts being adapted to have 25 their outer faces wiped by the contacts carried by the first mentioned arm, a second pair of overlying spaced contacts carried by the support in the same manner as the first mentioned pair of contacts, and adapted to 30 have the contact bridge plates passed there-between and engage their adjacent faces, and means for operating said member for shifting its arms in respect to said pairs of spaced contacts. 40

Signed at Seattle, Washington, this 11th day of August, 1922.

AMES C. McCANE.
